(57) **CLAIM**

The ornamental design for a wireless remote control, as shown and described.

DESCRIPTION

FIG. 1 is a perspective view of a wireless remote control, showing the new ornamental design;

FIG. 2 is a front view of the wireless remote control of FIG. 1;

FIG. 3 is a back view of the wireless remote control of FIG. 1;

FIG. 4 is a right view of the wireless remote control of FIG. 1;

FIG. 5 is a left view of the wireless remote control of FIG. 1;

FIG. 6 is a top view of the wireless remote control of FIG. 1; and,

FIG. 7 is a bottom view of the wireless remote control of FIG. 1.

The broken lines depict portions of the wireless remote control that form no part of the claimed design.
